D 5801

UNITED STATES PATENT OFFICE.

EDWARD POOLE, OF HALIFAX, ENGLAND, ASSIGNOR TO JOSEPH WILD
& CO., OF NEW YORK, N. Y.

DESIGN FOR A CARPET-PATTERN.

Specification forming part of Design No. 5,801, dated April 16, 1872.

Specification describing a new and original Design for a Carpet, invented by EDWARD POOLE, of Halifax, in the county of York, England.

The accompanying photograph fully illustrates my new design.

This invention relates to a new design for a carpet, in which there are four several kinds of ornamental figures and a new ornamental border.

The chief figure A is rectangular, with a zigzag outline, and containing a central ornament, B, remotely like the smallest figure C.

The two remaining figures, D and E, are both octagonal, but have different internal ornaments, as shown. The border F has zigzag inner and outer lines, and contains heart-shaped ornaments *a a*, that are connected by garlands *b b* of flowers.

I claim as my invention—

The design for a carpet, having the ornamental figures and borders, as shown.

EDWARD POOLE.
